UNITED STATES PATENT OFFICE.

CHARLES C. STANSELL, OF MIDDLEBOROUGH, ASSIGNOR TO HIMSELF, AND
AARON W. ROCKWOOD, OF NEWTON, MASSACHUSETTS.

IMPROVEMENT IN LAMPS.

Specification forming part of Letters Patent No. 35,979, dated July 22, 1862.

To all whom it may concern:

Be it known that I, CHARLES C. STANSELL, a citizen of the United States of America, and a resident of Middleborough, in the county of Plymouth and State of Massachusetts, have invented a new and useful or Improved Lamp; and I do hereby declare the same to be fully described in the following specification, and illustrated in the accompanying drawings, of which—

Figure 1 is a front elevation, and Fig 2 a vertical and longitudinal section, of a lamp provided with my invention.

The lamp in question is intended to burn coal-oil or various other liquid hydrocarbons rich in carbon.

The nature of my invention consists, first, in the arrangement of an annular flame-adjuster, made, as hereinafter described, with a stationary wick and wick-tube; second, in a peculiar construction of the said flame-adjuster, whereby it is prevented from charring the wick or too rapidly vaporizing a liquid hydrocarbon when in the wick.

In the drawings, A denotes a lamp, which is furnished with a stationary cylindrical wick-tube, B, that extends upward from the bottom, a, of the oil-reservoir b, and has an air-passage, c, leading through the stand of the lamp, so as to supply the tube B with air for the flame of the wick.

The wick shown at D is to be tubular and to surround and fit tightly on and project up to the top of the tube B, which should extend some distance above the lamp-cap E. A female screw, d, is cut in the mouth of the cap E, and receives the flame-adjuster F, or a male screw, e, made on its external surface. This flame-adjuster is tubular in form and surrounds the wick where it projects above the lamp-cap. At its upper part, or that marked f, the flame-adjuster is made to fit closely to the wick; but below this part, which need not be but about one-quarter of an inch in depth, the flame-adjuster is so constructed that there is an annular space, g, between it and the wick and surrounding the latter. The adjuster is made with a milled flange, h, by which it may be rotated when screwed into the lamp or the cap thereof. In case the body of the lamp be made of glass, a metallic cap

would be cemented on the neck of the opening of the oil-reservoir; but when the oil-reservoir is constructed entirely of metal the flame adjuster may be screwed directly into its neck or mouth.

The flame-adjuster is to be either screwed into the lamp-body or its cap, or is to be otherwise so applied thereto as to enable it to be readily either elevated or depressed and sustained in position after being so moved or adjusted with reference to the top of the wick. I prefer to fit the adjuster to the lamp by screws, as hereinbefore described, as such afford a ready and nice adjustment of it.

The annular space g within the adjuster and surrounding the wick prevents the heat of that part of the adjuster which is below the portion f not only from charring the wick but from causing a too rapid vaporizing of the oil in the upper part of the wick. It is desirable to have the bearing f of the adjuster on the wick very narrow. In proportion as we lower the adjuster on the wick the greater will be the surface or extent of wick exposed to the action of the flame when the lamp is lighted, and consequently the higher will be the flame. By means of the adjuster the height of the flame may be so regulated as to prevent the flame from developing smoke.

In other lamps the wick has to be raised in order to increase the height of the flame and lowered when it may be desirable to reduce such height. In my lamp, however, the wick is stationary and a tube surrounding it is movable. In this way I make a very simple lamp, in which no apparatus for either raising or lowering the wick is employed—a lamp in which coal-oil can be burned to excellent advantage without requiring any glass chimney or air-deflector such as are used in ordinary Argand lamps.

Fig. 3 denotes a vertical section of a lamp furnished with my invention and with devices by which the supply of air to the wick-tube does not pass up through the stand of the lamp, but goes from the upper part of the lamp down through a conduit or chamber, A', surrounding an oil-chamber, which in turn surrounds a wick-chamber, B', which immediately surrounds the wick C' and its supporting-tube D' and communicates with the oil-

reservoir E' of the lamp by one or more pipes. The air-conduit A', at its upper end, is open, but at its lower end it communicates with the internal air-passage, H', of the wick-tube. The flame-adjuster is shown at F as screwed on the intermediate tube, which separates the air-passage from the wick-chamber. The devices represented in Fig. 3 are simply to show a mode in which I have contemplated the application of the principle or character of my invention by which it may be distinguished from others.

The flame-adjuster may be constructed entirely of metal, or it may be made either wholly or partially of glass or other suitable material. A wick movable or adjustable relatively to its carrier is liable to gather carbon and become charred or burned; but when the wick is made stationary on the wick-tube and the flame-adjuster is applied to both in accordance with my invention the formation of carbonaceous or other deposits on or the charring of the wick at its top by the flame will be very much less likely to result, and consequently the height of the flame will not only be more even but less liable to vary, when the wick may once be so adjusted as not to smoke.

I do not claim a flame-adjuster as applied to a tube encompassing and fitting closely to a wick, and whether such wick be either solid or tubular my invention having reference to an arrangement of wick-tube, wick, and flame-adjuster. In such arrangement the wick surrounds the wick-tube, and is surrounded and in contact with the flame-adjuster, there being no tube intervening between the wick and the flame-adjuster and operating to insulate one from the other.

I therefore claim—

1. The above-described arrangement of an annular flame-adjuster, f, with a stationary tubular wick, D, and wick-tube B, the whole being to operate together as specified.
2. The combination of the flame-adjuster F in manner substantially as described—viz., with an annular space, g, arranged around the wick and immediately below the part f, which presses against the wick, the same being for the purpose as hereinbefore specified.

C. C. STANSELL.
